CLAIM

The ornamental design for a ring fixture for supporting bed canopy and window drapery fabrics, as shown and described.

DESCRIPTION

FIG. 1 is a top plan view of a ring fixture for supporting bed canopy and window drapery fabrics showing my new design, the bottom view being a mirror image of that shown; FIG. 2 is a front elevation view thereof;

FIG. 3 is a rear elevation view thereof; and,

FIG. 4 is a perspective view thereof, shown from the top front, and one side, the opposite side being a mirror image of that shown.
